HUGO EMANUEL TRAUGOTT SÜHLSSEN, OF HAMBURG, GERMANY, ASSIGNOR TO THE FIRM OF SIMPLO FÜLLFEDER GESELLSCHAFT VOSS, LAUSEN & DZIAMBOR, OF HAMBURG, GERMANY.

PENCIL HOLDER.

Application filed September 11, 1922. Serial No. 587,440.

To all whom it may concern:

Be it known that I, HUGO EMANUEL TRAUGOTT SÜHLSSEN, citizen of Germany, residing at Hamburg, Germany, have invented 5 certain new and useful Improvements in Pencil Holders (for which is filed an application in Germany, on 1st August, 1921, by the firm of Simplo Füllfeder Gesellschaft Voss, Lausen & Dziambor, of Hamburg, 10 with applicant's knowledge and consent), of which the following is a specification.

Pencil-holders are known in which by pressure on the head or button coupling and feed means are operated for acting upon a 15 push rod adapted to give the pencil-lead a hold or to push it forward, while on the return movement of the head or button the push rod will remain in its adjusted position together with the pencil lead. In the pencil- 20 holders known heretofore the lead is given a hold by a toothed push rod, which is moved forward on pressing a spring-pressed head-piece by the aid of a spring-pressed pawl, engaging the push rod, and which is locked 25 when the pawl is released. The means for feeding and locking the lead are liable to be broken and are unreliable in operation.

The drawbacks mentioned above are done away with by the present invention inasmuch as the push rod, which is to support or to hold the lead against an upward thrust, 30 is locked by a special coupling, consisting of a hollow cone and an annular frame, carrying a series of balls surrounding the push rod inside the hollow cone. By giving a relative movement to the hollow cone and the ball carrier frame the clamping action 35 may be discontinued so that the push rod together with the lead is left to itself to fall forward.

In the drawing two modes of constructing the pencil-holder are shown.

Fig. 1 is a longitudinal section of a pencil-holder, having a coupling which, when 45 opened, releases the push rod.

Figs. 2 and 3 are pencil-holders, in which by the aid of the coupling the feed of the pencil can be carried out.

In the construction shown in Fig. 1 the tubular main body 1 of the holder is firmly connected with a tube 2, projecting out at 50 its open end. Inside somewhere between the ends of this tube 2 there is a hollow cone 3, within which a ball carrier having

in the construction shown the shape of a 55 cone 4 is adapted to slide. In this cone 4 which has a shank 41 guided at the lower end in the bottom 21 of the tube 2, a series of spherical gaps 6 is arranged in a circle, filled by a corresponding number of balls 61, 60 which project out slightly through the outer surface of the cone 4 and are adapted to engage the inner conical surface of the hollow cone 3, while at the same time they also engage the push-rod 5, which projects centrally through a bore 42 of the ball carrier. Thus in the position shown in Fig. 1 the balls clamp the push rod between them. The upper end of the ball carrier or inner cone has a tubular prolongation 7 which 70 also surrounds the push rod 5 and which at its outer end engages a guide-piece 8. This guide-piece is connected by a pin 17, projecting open ended slots 9 in tube 2 with a tubular slide 10 which movably surrounds 75 the end of the tube 2 there being a filler 9' between members 24 and 10. A spiral-spring 11 surrounding the tube 7 bears against the guide piece 8 and the end of member 6, and a second spiral-spring 12 surrounding the 80 shank 41 bears with one end against the bottom 21 of the tube 2 and with the other end against the ball carrier 4.

It will be well understood that the pencil-lead 13, projecting out at the lower end or 85 point of the body 1, is held against inward movement by abutting against the lower end of the push rod 5 which latter, being held fast by the balls 61, prevents the lead from moving upwardly when writing with 90 the pencil-holder. A split friction guide 5' embraces rod 5. A second split friction guide 13' embraces lead 13 with sufficient friction to hold lead 13 in position against its own weight, but to allow the added 95 weight of rod 5, to push the lead 13 through guide 13'.

If desired to allow the pencil lead to project out to a greater extent the holder is held vertically with its point downward and 100 the tube slide 10 is shifted by thumb and finger towards the point of the holder. On account of this movement the ball carrier 4 is moved downward on account of the guide piece 8 being connected with the tubular slide and bearing against the tube 7. Thus the balls 61 are loosened and the push-rod 5 is released so that it can push the lead 105

out to any desired extent by its own weight. As soon as the tubular slide 10 is released it will be again moved upward by the spring 12, and also the cone 4 is returned by the 5 spring 12 against the tension of spring 11. Thus the balls 61 will again grip the push rod 5 and hold it in its adjusted position.

If it is desired to push the lead to a greater extent or fully into the holder, it 10 will be sufficient to hold the pencil-holder with the point of the lead down on the paper or table and to catch hold of the tubular slide 10 and shift it downward. Consequently the push rod 5 will be again released 15 and the lead will be moved inwardly to any desired extent, since the push rod 5 will no more offer any resistance.

The construction shown in Fig. 2 differs from that described above inasmuch as the 20 tube 2 is not connected with the tubular main body 1, but is movable relatively to the latter. The relative movement between the two tubes is limited by a slot 22 in the tube 2 and a pin 21 on the inside wall of 25 the main body 1, projecting into the slot 22. A spring 23 in the lower part of the body 1 tends to push the tube 2 upward, thus tending to loosen the coupling. By 30 pressing on the button 24 attached to the upper end of the tube 2 by being screwed into it, the tube 2 together with the complete coupling 3, 61, 4 will be moved downward as far as the slot 22 and pin 21 will allow. The push rod 5, being gripped by 35 the balls 61, will push out the lead 13 to a corresponding length. When the button 24 is released, the spring 23 will move the tube 2 back into its former position, the friction of the lead 13 and rod 5 against the sides 40 of the tubes 16 and 7, and within the split friction guides 13" and 5" being sufficient to retain the lead in its adjusted position, while the coupling 3, 61, 4 is temporarily loosened, from clutching rod 5, due to 45 spring 23 overcoming spring 12 and sliding member 3 away from cone 6 until this return motion is completed, whereupon again the spring 12 acts to press the ball carrier upward and to drive the balls between the 50 rod 5 and the hollow cone 3. The construction shown in Fig. 3 differs from that shown in Fig. 2 mainly inasmuch as the tubular slide is omitted and the button connected to the tube 2 is constructed to 55 form a cap 14 telescoping over the upper end of the holder 1. The relative movement of the tube 2 and the cap 14 on the main body 1 is limited by a pin 15 attached to the main body 1 and projecting 60 into a slot 15' in the tube 2. Moreover the tubular prolongation 7' of the ball carrier 4 projects out through the cap 14 as at 7" for a purpose hereinafter described. Split friction guides 5" and 13" retain 65 rod 5 and lead 13 in adjusted position.

When pressure is applied to the cap 14 the operation is similar to that described with reference to Fig. 2, that is to say the tube 2 will transmit the downward motion by the aid of the balls 61 to the push rod 70 5, and thus also to the lead 13. When the pressure on the cap 14 is released, the tube 2 will be returned to its former position by the spring 18, the push rod 5 remaining in its adjusted position as in the case of Figure 75 2 and being held by friction. Each time a further pressure is applied to the cap 14, the push rod 5 and together with it the pencil-lead will be further moved downward.

If it is desired to allow the lead to fully disappear, within the holder, so as to protect its point against being broken off, the end of the tube 7' projecting out at the cap 14 will be pushed inwardly so that the push 85 rod 5 will be no longer gripped by the balls 61 and thus the lead will easily slide upward, when the pencil-lead is pushed forward. The same operation will take place when a new lead is to be inserted.

I claim:

1. A pencil-holder comprising a tubular casing, a centrally guided push rod abutting with one end against the pencil-lead, a coupling adapted to lock the push rod 95 in any adjusted position, a spring tending to hold the coupling in operative position and a second spring tending to loosen the coupling.

2. A pencil-holder comprising a tubular 100 casing, a centrally guided push rod abutting with one end against the pencil lead, a coupling consisting of a hollow cone and a series of balls intermediate the hollow cone and the push rod, whereby to clamp 105 the push rod in any desired position, and two springs, one tending to couple, and the other tending to uncouple, the coupling member.

3. A pencil-holder comprising a tubular 110 casing, a centrally guided push rod abutting with one end against the pencil-lead, a tube slidably guided within the tubular casing and carrying a hollow cone, a series of balls intermediate the hollow cone and 115 the push rod, whereby to couple the push rod with the said tube and two springs, one tending to couple, and the other tending to uncouple, the coupling member.

4. A pencil-holder comprising a tubular 120 casing, a centrally guided push rod abutting with one end against the pencil-lead, a tube slidably guided within the tubular casing, and carrying a hollow cone, a series of balls intermediate the hollow cone and 125 the push rod, whereby to couple the push rod with the said tube, the said tube projecting out of the tubular casing, a button attached to the tube, a slot- and pin-connection between the casing and the tube, 130

limiting the relative movement between these two parts and two springs, one tending to couple, and the other tending to uncouple, the coupling member.

5 5. A pencil-holder comprising a tubular casing, a tube slidable within and projecting out of the casing at one end, a pin- and slot-connection between the said tube and the casing, a spring within the casing tending to push the tube in one direction, a button on the outer end of the tube, by the pressing down of which the tube can be moved against the action of the spring to an extent limited by the pin- and slot-connection, a lead push rod guided centrally within the holder, a coupling between the push rod and the said tube and two opposing resilient members acting on said coupling.

20 6. A pencil-holder comprising a tubular casing, a tube slidable within and projecting out of the casing with one end, a pin- and slot-connection between the said tube and the casing, a spring within the casing tending to push the tube in one direction, a button on the outer end of the tube, by the pressing down of which the tube can be moved against the action of the spring to an extent limited by the pin- and slot-connection, a lead push rod guided centrally within the holder, a coupling between the push rod and the said tube, comprising a hollow cone and a carrier, carrying a number of balls adapted to be clamped between the push rod and the hollow cone, and a second spring tending to push the ball carrier into clutching position, one tending to couple, and the other tending to uncouple, the coupling member.

40 7. A pencil-holder comprising a tubular casing, a tube slidable within and projecting out of the casing with one end, a pin- and slot-connection between the said tube and the casing, a spring within the casing tending to push the tube in one direction, a button on the outer end of the tube, by the pressing down of which the tube can be moved against the action of the spring to

an extent limited by the pin- and slot-connection, a lead push rod guided centrally within the holder, a coupling between the push rod and the said tube, comprising a hollow cone and a carrier, carrying a number of balls adapted to be clamped between the push rod and the hollow cone, and a second spring tending to push the ball carrier into operative position, an outer tubular slide surrounding the said tube intermediate the button and the end of the tubular casing, a member arranged within the tube and adapted to bear against a prolongation of the ball carrier and connected to the tubular slide by a pin, and a slot in the wall of the tube through which the said pin passes.

15 8. A pencil-holder comprising a tubular casing, a tube slidable within and projecting out of the casing with one end, a pin- and slot-connection between the said tube and the casing, a spring within the casing tending to push the tube in one direction, a button on the outer end of the tube, by the pressing down of which the tube can be moved against the action of the spring to an extent limited by the pin- and slot-connection, a lead push rod guided centrally within the holder, a coupling between the push rod and the said tube, comprising a hollow cone and a carrier, carrying a number of balls adapted to be clamped between the push rod and the hollow cone, and a second spring tending to push the ball carrier into operative position, an outer tubular member surrounding the said tube intermediate the button and the end of the tubular casing, an abutment arranged within the tube and adapted to bear against a prolongation of the ball carrier and connected to the tubular slide by a pin, a slot in the wall of the tube through which the said pin passes, and a third spring surrounding the prolongation of the ball carrier and biasing the ball-carrier toward inoperative position.

In testimony whereof I have signed my name to this specification.

HUGO EMANUEL TRAUGOTT SÜHLSEN.
